UNITED STATES PATENT OFFICE

163,866

FIGURINE OR THE LIKE

Myra Halpert, St. Albans, N. Y.

Application March 6, 1951, Serial No. 14,400

Term of patent 7 years

(Cl. D29—23)

To all whom it may concern:

Be it known that I, Myra Halpert, a citizen of the United States of America, residing in St. Albans, New York, county of Queens, and State of New York, have invented a new, original, and ornamental Design for a Figurine or the like, of which the following is a specification, reference being had to the accompanying drawing, forming part thereof, wherein,

I claim:

The ornamental design for a figurine or the like, substantially as shown.

MYRA HALPERT.
